DESCRIPTION

FIG. 1 is a front perspective view of the hands-free kit of the present invention, with broken lines showing environmental detail of electrical connectors, pushbuttons, telephone connection pins, a telephone cable jack, and surface ornamentation;

FIG. 2 is a left-side rear lower perspective view thereof, with broken lines showing environmental detail of a structural loop, a power input jack, and a connector for removably mounting the hands-free kit on a support;

FIG. 3 is a front elevation view thereof;

FIG. 4 is a rear elevation view thereof;

FIG. 5 is a auxiliary left side elevation view thereof, from a vantage in alignment with the face of a loudspeaker of the hands-free kit, with broken lines showing environmental detail of an exemplary wireless device mounted in the front of the hands-free kit;

FIG. 6 is a right side elevation view thereof, with environmental detail of the exemplary wireless device omitted;

FIG. 7 is a top plan view thereof; and,

FIG. 8 is a bottom plan view thereof.

The broken lines in FIGS. 1-8 are illustrative of environmental structure only and form no part of the claimed design.
